UNITED STATES PATENT OFFICE.

WILLIAM M. MANLY, OF CHICAGO, ILLINOIS.

DESIGN FOR A TWINE-HOLDER.

SPECIFICATION forming part of Design No. 23,521, dated July 31, 1894.

Application filed April 23, 1894. Serial No. 508,721. Term of patent 14 years.

To all whom it may concern:

Be it known that I, WILLIAM M. MANLY, a citizen of the United States, residing in Chicago, in the county of Cook and State of Illinois, have invented a new and original Design for Twine-Holders, of which the following is a specification, reference being had to the accompanying drawings, forming a part thereof.

The leading feature of my design consists in a twine holder comprising a horizontal base, a post extending upward from the center of the base, studs at either side of said center post also extending upward from the base, a cross head at the top mounted upon said post, wires extending from the end portion of the cross head to the end portion of the base, and a cross bar secured upon the post midway between its ends.

The drawings show at Figure 1 a front elevation and at Fig. 2 a cross vertical section of my design, and in said drawings A repre-

sents the base, B the post, C the studs, D the cross head, E E the wires and F the cross bar.

As plainly illustrated the base has an ornamental longitudinal panel upon its front surface and pointed ends; the post is reticulated throughout its length with rectangular openings b. The cross head is also reticulated with variously shaped openings d and with floral designs d' at its ends. The cross bar is provided with Y-shaped openings f. e represents the weights.

H represents the eagle surmounting the cross head.

I claim—

The design for a twine holder, substantially as herein shown and described.

WILLIAM M. MANLY.
